UNITED STATES PATENT OFFICE.

JOSEPH W. STEELMAN, OF PHILADELPHIA, PENNSYLVANIA.

FUSE-CARTRIDGE.

1,114,654.

Specification of Letters Patent.

Patented Oct. 20, 1914.

Application filed May 16, 1913. Serial No. 768,100.

To all whom it may concern:

Be it known that I, JOSEPH W. STEELMAN, a citizen of the United States, residing at Philadelphia, in the county of Philadelphia and State of Pennsylvania, have invented new and useful Improvements in Fuse-Cartridges, of which the following is a specification.

This invention relates to improvements in fuse cartridges and has particular application to a cartridge wherein the fusible element may be renewed whenever the same has become burned out or otherwise mutilated.

In carrying out the present invention, it is my purpose to provide a fuse cartridge which will embody among other features a tubular body preferably composed of insulated material and having the inner surfaces at the opposite ends thereof flared outwardly, and a pair of wedge-shaped blocks disposed within each end thereof and having the confronting faces thereof designed to grip the respective end of the fusible element or strip, the ends of the tubular body being closed by means of caps which latter act upon the wedge-shaped blocks to force the same inwardly of the tube and so produce a clamping action upon the fusible element or strip.

It is also my purpose to provide a device of the class described which will embrace the desired features of simplicity, efficiency and durability coupled with cheapness of cost in manufacture and marketing and which may be readily assembled and disassembled so as to facilitate refilling of the cartridge.

With the above and other objects in view, the invention consists in the construction, combination and arrangement of parts hereinafter set forth in and falling within the scope of the claim.

In the accompanying drawing; Figure 1 is a longitudinal sectional view through a fuse cartridge constructed in accordance with the present invention, the fusible strip being shown in edge elevation. Fig. 2 is a similar view taken at right angles to Fig. 1 showing the fusible strip and certain of the wedge blocks in plan. Fig. 3 is a perspective view of one of the caps, and Fig. 4 is

a similar view of a pair of coöperating wedge blocks.

Referring now to the accompanying drawing in detail, the numeral 1 designates a tubular body composed of insulating material and having the inner surface thereof at the opposite ends flared outwardly as at 2 and the exterior surface thereof at such end threaded as at 3. Mounted within each flared end of the tubular body 1 is a pair of wedge blocks 4, the confronting faces of the blocks of each pair being flat as at 5 and are designed to receive the respective ends of a fusible strip 6 disposed longitudinally and centrally of the body 1. Threadedly engaging each end of the body 1 is a cup-shaped cap 7 having the side wall thereof threaded interiorly to engage the exterior threads in the respective end of the body, and the end wall thereof formed with an aperture 8 coaxial with the tubular body 1 to receive the free end of the fusible strip 6 beyond the wedge blocks, the wall of such opening 8 being beveled or flared outwardly as at 9 so as to afford convenient opening for the fingers when the caps have been loosened and it is desired to refill the cartridge, as when the fusible element has burnt out.

From the foregoing description taken in connection with the accompanying drawing, the construction, mode of operation and manner of employing my invention will be readily apparent. It will be seen that I have provided a fuse cartridge wherein the fusible strip may be readily replaced and wherein the component parts may be readily disassembled when it is desired to clean or repair the cartridge, while when replacing a mutilated fusible strip, it is only necessary to loosen the caps at the ends of the tubular body so that the wedge blocks will readily receive the strip, the caps being subsequently tightened up so as to produce a clamping action between the confronting surfaces of the wedge blocks and the respective end of the fusible strip.

I claim:

A fuse cartridge comprising a tubular body of insulating material having the inner surfaces of the ends thereof flared outwardly and the exterior surfaces screw threaded, a pair of wedge-shaped blocks

mounted within each end of said body and having flat confronting faces, a fusible strip disposed longitudinally of said body and having the opposite ends thereof arranged between the confronting faces of said blocks, and cup-shaped caps having the side walls thereof threadedly engaging the ends of said body and the end walls thereof apertured to receive the free ends of said

strip beyond said blocks, the apertures in said caps having beveled walls substantially as, and for the purpose, described.

In testimony whereof I affix my signature in presence of two witnesses.

JOSEPH W. STEELMAN.
